HIGH FREQUENCY AMPLIFIER CIRCUITS

Maximiliaan Julius Otto Strutt and Aldert van der Ziel, Eindhoven, Netherlands; vested in the Alien Property Custodian

Application January 29, 1941, Serial No. 376,456
In the Netherlands March 26, 1940

12 Claims. (Cl. 179—171)

In our copending application, Ser. No. 333,088, filed May 3, 1940, there is described a high-frequency amplifier circuit comprising at least one amplifier valve whose cathode is provided with at least two leads, one of which, for the oscillations to be amplified, is included in the input circuit and another in the output circuit, and in which capacities are connected between the control grid and the point of the cathode which is connected to the cathode lead included in the input circuit and between the control grid and that end of the cathode lead included in the output circuit which is not connected to the cathode, and one or both cathode leads comprises or comprise impedances of which at least one has an inductive character, said capacities and impedances being proportioned in such manner that the input damping is approximately zero or negative.

The invention relates to a cascade circuit comprising at least two amplifying stages built up in the manner above-described.

According to the invention, in a cascade circuit of the said kind, at least at the stages preceding the last stage, that end of the cathode lead included in the output circuit which is remote from the cathode is connected to earth for high-frequency currents.

In order that the invention may be clearly understood and readily carried into effect it will now be described more fully with reference to the accompanying drawings, in which

Fig. 1 shows a circuit according to the earlier application,

Figs. 2, 3 and 4 show cascade circuits according to the present invention.

Fig. 4a shows a modification of a portion of the circuit disclosed in Fig. 4.

The circuit shown in Fig. 1 comprises an amplifier valve 1 having a cathode 2 which is provided with two leads, a control grid 3, a screening grid 4, a suppressor grid 5 and an anode 7. For the sake of simplicity Fig. 1 only shows the high-frequency connections of the various electrodes, the direct-current connections being omitted.

The high frequencies to be amplified are fed to an input oscillatory circuit 12 which is connected on the one hand to the control grid 3 and on the other hand, via one of the cathode leads, to the cathode 2. The anode 7 is connected to the cathode 2 via an output-oscillatory circuit 13, from which the amplified oscillations are taken off, and via the other cathode lead.

The cathode leads include inductances L₁ and L₂ and the point 8 of the inductance L₁, which point is adjacent to the cathode, is connected to the control grid 3 via a capacity C₁ and the end of the inductance L₂ (9) which is remote from

the cathode is connected to the control grid via a capacity C₂.

The screening grid 4 is connected, via a capacity C₃, to that end of the inductance L₂ which is remote from the cathode so that the natural capacity between the control grid and the screening grid assists in the action of the capacity C₂. The suppressor grid 5 is also connected to the point 9.

If the elements L₁, L₂, C₁ and C₂ of the circuit described so far are correctly proportioned this circuit permits of the input damping, which occurs due to the finite transit time of the electrons, being suppressed entirely so that the consequential input damping becomes zero or even negative. The elements L₁, L₂, C₁ and C₂ can be formed in part but not all of them by the natural inductances of the cathode leads and the natural tube capacities.

In practice the circuit arrangement is fitted on the metal mounting plate of large surface (chassis) and the circuit must be earthed at at least one point for high-frequency currents, that is to say, be connected to the mounting plate.

In the usual high-frequency amplifier circuit arrangements both that end of the input oscillatory circuit 12 which is remote from the control grid and that end of the output oscillatory circuit 13 which is remote from the anode are frequently connected for high-frequency currents to the chassis. Such double earthing is, however, inadmissible in the present case because the ends 9 and 21, remote from the cathode, of the inductances L₁ and L₂ would thus be short-circuited and hence the two cathode leads would be united to form a single unit. In the circuit arrangement shown in Fig. 1 only one point should therefore be connected to earth for high-frequency currents.

Since the parts of the two cathode leads which are located within the tube form part of the inductances L₁ and L₂ the cathode 2 is inaccessible. We therefore only have the choice between earthing a point of the input circuit and earthing a point of the output circuit.

In this it should be taken into account that that end of the output oscillatory circuit 13 which is connected to the anode will generally manifest a rather substantial parasitical capacity 50 relatively to the chassis, which is denoted by 20 in Fig. 1. Now, if a point of the input circuit, say the point 21, is earthed, part of the anode current will flow to earth via the capacity 20 and thence pass to the cathode 2 via the inductance L₁. This causes an undesired retroaction which also brings about a damping of the input-oscillatory circuit. Since the capacity 20 forms part of the output-oscillatory circuit the current passing through this capacity may be larger under certain circumstances than the total anode cur-

rent and the desired reduction of the damping of the input-oscillatory circuit will not therefore be obtained by this phenomenon.

Earthing a point of the input circuit is therefore only permissible if the capacity 20 is reduced to a minimum value, as may be effected by capacitatively screening the accessible part of the anode lead and the output oscillatory circuit 13 by means of a screen which is connected to the point 9.

If a point of the output circuit is connected to earth the phenomenon described cannot occur and the said capacitative screening of the output circuit is consequently redundant. In this case the earth connection will preferably be arranged at the point 9 so that the total anode current passes through the inductance L_2 and the tuning condenser of the circuit 13 is also earthed.

As is apparent from the above, in a circuit comprising a single amplifying stage both earthing of the point 21 and earthing of the point 9 are possible. This, however, is no longer the case in a cascade circuit.

If, as a matter of fact, the amplifying stage shown in Fig. 1 is followed by a second similar stage the output oscillatory circuit 13 is coupled in some manner to the control grid of the next tube and this control grid always has a comparatively considerable capacity relatively to earth. In this case the capacity 20 can therefore no longer be removed by a screen.

It is on the basis of this recognition according to the invention, in a cascade circuit, at least at the stages preceding the last stage, the point 9 is alone always connected to earth.

Examples of cascade circuits according to the invention are shown in Figs. 2, 3 and 4 in which the supply of the tubes is also indicated. Each of the cascade circuits shown comprises two stages in which those elements of the second stage which also occur in the first stage are designated by primed reference numerals.

In the circuit shown in Fig. 2 the points 9, 9' in both stages are connected to earth in a high-frequency manner through condensers 23, 23' respectively which constitute a short-circuit for the oscillations to be amplified.

The condensers 23 and 23' are connected in parallel with resistances 24 and 24' across which the anode direct current brings about a voltage drop which serves as bias for the control grid 3, 3'. For this purpose a grid condenser 22, 22' is arranged between the input oscillatory circuit and the control grid, whilst at the same time the control grid 3, 3' is connected to earth through a high-ohmic leak 25, 25'.

The positive biases of the screening grids 4, 4' and the anodes 7, 7' are supplied through a resistance 26, 26' and 27, 27'.

The output oscillatory circuit 13 of the first stage also constitutes the input oscillatory circuit of the second stage. Since the point 9' of the second stage should alone be earthed, the end of the oscillatory circuit 13 which is remote from the anode 7 is not connected to earth but is connected, through a condenser 28, to that end 21' of the cathode lead included in the input circuit which is remote from the cathode 2'. The anode alternating current of the first stage consequently flows from the anode 7 through the circuit 13, the condenser 28, the inductances L_1 and L_2 and the condenser 23' to earth and thence through the condenser 23 and the inductance L_2 to the cathode 2. Since the anode current of the first stage is approximately in

anti-phase with the anode current of the second stage the decrease of the input damping of the second stage which is aimed at by the invention is assisted by the anode current of the first stage.

The circuit shown in Fig. 2 may be enlarged with any number of stages. If the second stage is followed by a third stage the anode 7' is connected through the condenser 22'' to the control grid of the third stage and that end of the oscillatory circuit 13' which is remote from the anode 7' through the condenser 28' to that end of the cathode lead included in the input circuit which is remote from the cathode. If the second stage is also the last stage the circuit 13' may be connected to earth through the condenser 28'.

Fig. 3 shows a circuit which can only be used if the second stage is also the last stage. The first stage of the circuit is substantially similar to the first stage of the circuit shown in Fig. 2 except that the output oscillatory circuit 13 is connected to earth. To avoid a short-circuit of the source of anode voltage the circuit 13 includes a blocking condenser 29.

The circuit 13 also constitutes the input oscillatory circuit of the second stage so that the input circuit of the second stage is earthed. The anode direct current of the second stage in consequence flows across the cathode lead included in the input circuit so that the network 31, 32 which serves for the generation of the control grid bias has also to be included in this cathode lead. The bias set up is impressed on the control grid 3' by means of a leak 30.

The output oscillatory circuit 13' of the second stage is connected in a high-frequency manner through a condenser 33 to the point 9'.

The accessible part of the anode lead and the output oscillatory circuit 13' of the second stage are screened capacitatively relatively to earth by means of a screen 34 connected through a conductor 35 to the point 9'.

Lastly, Fig. 4 shows a circuit in which the stages are entirely separated from each other and in which the output oscillatory circuit 13 of the first stage is coupled inductively to the input oscillatory circuit 12' of the second stage. The two stages are quite identical. In both stages the points 9, 9' are earthed in a high-frequency manner and the output oscillatory circuits 13, 13' are connected to earth through respectively the condenser 36, 36'.

Instead of using an inductive coupling between the circuits 13 and 12' use may be made of a capacitative coupling, for example by means of a coupling condenser 22'' arranged between the anode 7 and the control grid 3', as shown in Fig. 4a.

The circuit shown in Fig. 4 may be enlarged with any number of stages.

What we claim is:

1. A cascade circuit comprising at least two high-frequency amplifying stages each of which comprises an amplifier valve whose cathode is provided with at least two leads one of which, for the oscillations to be amplified, is included in the input circuit and another in the output circuit and in which a capacity is connected between the control grid and that end of the cathode lead remote from the cathode included in the output circuit and the latter cathode lead comprises an impedance of an inductive character, said capacity and impedance being proportioned in such manner that the input damping is zero or nega-

tive, wherein at least at those stages which precede the last stage solely that end of the cathode lead included in the output circuit which is remote from the cathode is connected to earth in a high-frequency manner.

2. A cascade circuit as claimed in claim 1, in which the output oscillatory circuit of the preceding stage also constitutes the input oscillatory circuit of the next following stage, wherein the oscillatory circuit concerned is not earthed in a high-frequency manner but is connected to that end of the cathode lead of the said following stage included in the input circuit which is remote from the cathode.

3. A cascade circuit as claimed in claim 1, in which the output oscillatory circuit of the stage preceding the last stage also constitutes the input oscillatory circuit of the last stage, wherein the oscillatory circuit concerned is earthed in a high-frequency manner and the accessible part of the anode lead and the output oscillatory circuit of the last stage are screened capacitatively relatively to earth.

4. A cascade circuit as claimed in claim 1, in which use is made of completely separated stages, wherein the output oscillatory circuit of a preceding stage is coupled inductively or capacitatively to the input oscillatory circuit of a following stage.

5. A multi-stage circuit for the amplification of high frequencies, each stage comprising an electron discharge tube provided with at least a cathode, a signal input grid and an anode, the cathode having at least two leads connected thereto, input and output circuits connected respectively to the input grid and to the anode, the grid return of the input circuit being connected to one of the cathode leads, the plate return of the output circuit being connected to the other cathode lead, a condenser connected between the signal input grid and that end of the cathode lead included in the output circuit which is remote from the cathode, and means in one of the stages preceding the last for grounding with respect to high frequencies that end of the cathode lead included in the output circuit which is remote from the cathode.

6. A multi-stage circuit for the amplification of high frequencies, each stage comprising an electron discharge tube provided with at least a cathode, a signal input grid and an anode, the cathode having at least two leads connected thereto, input and output circuits connected respectively to the input grid and to the anode, the grid return of the input circuit being connected to one of the cathode leads, the plate return of the output circuit being connected to the other cathode lead, a condenser connected between the signal input grid and that end of the cathode lead included in the output circuit which is remote from the cathode, and a condenser shunted by a resistance connected in each stage between that end of the cathode output lead remote from the cathode and ground.

7. A multi-stage circuit in accordance with the invention defined in claim 6 wherein the output circuit of a preceding stage also constitutes the input circuit of the next following stage, means for capacitively coupling the high potential end of said circuit to the signal input grid of said

next following stage, and means for capacitively coupling the low potential end of said circuit to the cathode lead included in the input circuit of said next following stage at the end thereof remote from the cathode.

8. A multi-stage circuit according to the invention defined in claim 6 wherein the output circuit of a preceding stage also constitutes the input circuit of the next following stage, means for capacitively coupling the high potential end of said circuit to the signal input grid of said next following stage, and means for connecting the low potential end of said circuit to ground.

9. A multi-stage circuit according to the invention defined in claim 6 wherein the output circuit of a preceding stage also constitutes the input circuit of the next following stage, means for capacitively coupling the high potential end of said circuit to the signal input grid of said next following stage, means for connecting the low potential end of said circuit to ground, and means for capacitively screening the accessible part of the anode lead and the output circuit of said next following stage.

10. A multi-stage circuit in accordance with the invention defined in claim 6 wherein the output circuit of a preceding stage is inductively coupled to the input circuit of the next following stage.

11. A multi-stage circuit for the amplification of high frequencies, each stage comprising an electron discharge tube provided with at least a cathode, a signal input grid, a screen grid and an anode, the cathode having a pair of leads connected thereto, an impedance connected to one of the cathode leads, input and output circuits connected respectively to the input grid and to the anode, the plate return of the output circuit being connected to the low potential end of the impedance connected to said one cathode lead, the grid return of the input circuit being connected to the other cathode lead at the end remote from the cathode, capacitive means connected between the signal input grid and the low potential end of the cathode impedance included in the output circuit, and means in one of the stages preceding the last for grounding with respect to high frequencies that end of the cathode impedance included in the output circuit which is remote from the cathode.

12. A multi-stage circuit for the amplification of high frequencies, each stage comprising an electron discharge tube provided with at least a cathode, a signal input grid, a screen grid and an anode, the cathode having a pair of leads connected thereto, an impedance connected to one of the cathode leads, input and output circuits connected respectively to the input grid and to the anode, the plate return of the output circuit of at least one stage being connected through a capacity and shunt resistance to the low potential end of the impedance connected to said one cathode lead, the grid return of the input circuit being connected to the other cathode lead at the end remote from the cathode, and capacitive means connected between the signal input grid and the low potential end of the cathode impedance included in the output circuit.

MAXIMILIAAN JULIUS OTTO STRUTT,
ALDERT VAN DER ZIEL.
